DESIGN FOR A HOLDER FOR RATION CONTAINER

Nicholas T. Naranick, United States Army,
Casper, Wyo.

Application October 2, 1942, Serial No. 168,393

Term of patent 3½ years

To all whom it may concern:

Be it known that I, Nicholas T. Naranick, United States Army, a citizen of the United States, residing at Casper, county of Natrona, State of Wyoming, have invented a new, original, and ornamental Design for a Holder for Ration Container, of which the following is a specification, reference being had to the accompanying drawing, forming part thereof.

Fig. 1 is a plan view of a holder for ration container, showing my new design,

Fig. 2 is an edge view of said holder, and

Fig. 3 is a bottom plan view of said holder when folded.

I claim:

The ornamental design for a holder for ration container, as shown.

NICHOLAS T. NARANICK.
